LUMINOUS ATTACHMENT FOR LOCK BARRELS

Bernard Heinz, Scranton, Pa.

Application December 29, 1952, Serial No. 328,387

2 Claims. (Cl. 250—76)

This invention relates to a luminous attachment for lock barrels,

An object is to provide a self-luminous guide for a keyhole of a lock so made that the luminous means provides a first guide element leading to a second guideway, and thence into the keyhole whereby the keyhole will not only be apparent in the dark, but also whereby in the dark, as well as in the light, the key may be applied to and inserted in the lock without a person having to jab at the lock to find the keyhole.

Another object of this invention is to provide a luminous attachment which in cooperation with an auxiliary key guide will permit the insertion of the key into the keyhole of the lock barrel without jabbing.

A further object of this invention is to provide a luminous attachment including an improved auxiliary key guide and means for holding the auxiliary key guide in registry with the keyhole of the lock barrel.

A further object of this invention is to provide an attachment for a lock embodying a luminous ring adapted to encircle the outer end of a lock barrel and to be secured to the escutcheon plate for the lock structure so that the key may be inserted in the keyhole without jabbing of the key.

With the above and other objects in view, my invention consists in the arrangement, combination and details of construction disclosed in the drawings and specification, and then more particularly pointed out in the appended claims.

In the drawings—

Figure 1 is a detailed front elevation of a luminous guide attachment for a lock constructed according to an embodiment of this invention.

Figure 2 is a sectional view taken on the line 2—2 of Figure 1.

Figure 3 is a sectional view taken on the line 3—3 of Figure 2.

Figure 4 is a fragmentary sectional view taken on the line 4—4 of Figure 3.

Figure 5 is a detailed front elevation of the guide lock,

Figure 5A is a sectional view taken on the line 5A—5A of Figure 5.

Figure 6 is a detailed front elevation of the key guide,

Figure 6A is a sectional view taken on the line 6A—6A of Figure 6.

Figure 6B is a sectional view of the key guide, showing a modified form of the guide,

Figure 7 is a detailed front elevation of a modified form of this invention,

Figure 8 is a sectional view taken on the line 8—8 of Figure 7.

Figure 9 is a detailed front elevation of another modification of this invention,

Figure 10 is a fragmentary sectional view taken on the line 10—10 of Figure 9.

Figure 11 is a detailed side elevation of another form of this invention,

2

Figure 12 is a detailed front elevation of the lock structure shown in Figure 11.

Figure 13 is a fragmentary sectional view taken on the line 13—13 of Figure 12.

Referring to the drawings and first to Figures 1 to 5A inclusive, the numeral 15 designates generally a conventional lock structure of the tumbler type, embodying a barrel 16 adapted to be rotated by means of a key which is extended through a key opening 17. The lock structure 15 includes a flange 18 which is adapted to be disposed at the outer side of a door or closure 19.

An escutcheon plate 20 is disposed at the outer end of the lock 15 and is provided with a rearwardly projecting annular flange 21 adapted to abut against the outer side of the closure 19.

A ring 22, having an inner annular flange 23 is adapted to engage about the flange 18 of the lock structure 15, and the cylindrical flange 22 is provided with an oppositely disposed pair of outwardly projecting locking flanges 24 which are engageable beneath a pair of inwardly projecting locking flanges 25 carried by the annular flange 21.

A ring-shaped substantially transparent member 26 is disposed within an outwardly projecting annular flange 27 carried by the plate 20, being secured in the flange 27 by pressing the outer end of the flange 27 into a shallow annular groove 28 formed in the periphery of the ring 26. The inner end of the ring 26 has radium or other luminous material 29 painted thereon, whereby the ring 26 will be luminous in the dark.

A key guide 30 is disposed within the ring 26 and is formed with an annular flange 31 engaging in an opening 32 formed in the plate 20. The key guide 30 is held against rotation relative to the lock barrel 16 so that the keyhole 33 in the guide 30 will be in alignment with the keyhole 17, by means of a disc-shaped plate 34 which bears against the inner end of the guide 30 and the outer end of the barrel 16.

The plate or disc 34 is formed with a keyhole 35 and is also formed with an inwardly projecting finger 36 which is engageable in the lower end of the keyhole 17. The plate 34 is also provided with an outwardly projecting finger 37 at the opposite end of the keyhole 35, which is engageable in a keyhole 33 of guide 30 at the upper end of the keyhole 33. In this manner the guide 30 will be locked against rotation relative to the lock barrel 16. The outer side of the guide 30 is of concave configuration, as indicated at 38, so that when a key is inserted within the ring 26, the key will slide over the concave surface 38 into the keyhole 33. This sliding action of the key will eliminate any jabbing of the end of the key against the outer or auxiliary key guide 30.

Referring now to Figure 6B, there is disclosed a modified form of key guide which is similar to the guide 30, with the exception that the outer side 39 of the key guide is of convex configuration. In other respects the guide 30a is similar to the guide 30.

Referring now to Figures 7 and 8, there is disclosed another modification of this invention, wherein the luminous ring 40 is mounted on the outer end of a lock structure which is mounted in a door knob 41. The lock structure 42 which is within the door knob 41, includes a lock barrel 43 rotatable within the lock housing 44, and the latter is formed with an outer annular flange 45. A cap generally indicated at 46 engages over the outer end of the lock structure 42 and includes an annular flange 47 which is disposed tightly about the annular flange 45, being pressed or otherwise firmly secured thereon.

The outer wall 48 of the cap 46 is provided with an annular flange 49 within which the ring 40 is secured

by crimping the flange 48 into a shallow groove 50 which is formed in the ring 40. A key guide 51, similar to either guide 30 or guide 30a, is rotatably mounted interiorly of the ring 40 and within an opening 52 which is formed in the outer wall 48. The guide 51 is held against rotation relative to the lock barrel 43 by means of a holding disc 53, similar to disc 34.

Referring now to Figures 9 and 10, there is disclosed another modification of this invention, wherein a luminous ring 54 is mounted in the outer end of a sleeve 55. The sleeve 55 is telescoped over the outer end of a cylindrical shell 56 which encases a lock barrel 57. A key guide 58, similar to the guide 30 or the guide 30a, is rotatably disposed within the sleeve 55 and at the inner end of the ring 54. A locking member 59 is interposed between the guide 58 and the outer end of the barrel 57 and is similar in every detail to the guide locking member 34, shown in Figures 5 and 5A.

Referring now to Figures 11, 12 and 13 there is disclosed another modification of this invention wherein a luminous ring 60 is mounted in a cylindrical housing 61 having a reduced cylindrical member 62 extending from the inner end thereof, which is tightly mounted on the outer end of a lock structure 63. The lock structure 63 is slidable in a lock housing 64, being movable inwardly of the housing 64 when a key is inserted within the lock barrel 65. A key guide 66, similar to guide 30 or guide 30a, is interposed between the ring 60 and the shoulder 67 formed between the housing 61 and the sleeve 62. A locking member 68, similar to locking member 34, is interposed between the guide 58 and the outer end of the lock barrel 57, for holding the guide 58 against rotation relative to the barrel 57.

The configuration of the luminous attachment herein disclosed with the improved key guide is such that when the end of the key to be inserted into the lock barrel strikes any point from the inner portion of the luminous ring to the keyhole, the key will slide inwardly toward the keyhole. In this manner there will be no fumbling

or jabbing of the key as the key will smoothly slide in the direction of the keyhole.

I do not mean to confine myself to the exact details of construction herein disclosed, but claim all variations falling within the purview of the appended claims.

What I claim is:

1. A luminous attachment for locks comprising a transparent ring, a luminous coating on the inner end of said ring, means fixedly securing said ring relative to the lock structure with said ring concentric to the lock barrel, a key guide plate interposed between said ring and the outer end of the lock barrel, said plate having a keyhole, a lock plate interposed between said guide plate and the outer end of the lock barrel, and oppositely extending locking fingers carried by said lock plate engageable respectively in the keyhole of said guide plate and the keyhole of the lock barrel for locking said guide plate relative to said lock barrel.

2. A luminous attachment for locks comprising a luminous ring, a circular holder about said ring, a plate fixed to the inner end of said holder, a cylindrical flange carried by said plate, a pair of oppositely disposed inwardly projecting locking flanges carried by said cylindrical flange, a cylindrical member engageable about the outer end of the lock structure, an inwardly projecting annular flange carried by said member engageable with said lock structure for holding said member against outward movement, and a pair of outwardly projecting locking flanges carried by said member engageable with said first-named locking flanges to thereby lock said plate relative to said lock structure with said ring concentric to the lock barrel.
